UNITED STATES PATENT OFFICE.

MONROE GUETT, OF HARTFORD, CONNECTICUT, ASSIGNOR TO THE HART & HEGEMAN MANUFACTURING COMPANY, OF HARTFORD, CONNECTICUT, A CORPORATION OF CONNECTICUT.

RECEPTACLE.

Application filed June 5, 1924. Serial No. 718,105.

My invention relates to certain improvements in receptacles for fuse plugs, or electric lamps.

The object of the invention is to provide a receptacle having a standard shell, in which can be permanently secured a shell of less diameter to accommodate fuse plugs, and, in some instances, lamps having bases smaller than the standard size.

10 In the accompanying drawings:

Fig. 1 is a face view of a receptacle of the ordinary type;

Fig. 2 is a sectional view on the line 2—2,

Fig. 1;

15 Fig. 3 is a sectional view showing the shell of less diameter inserted in the receptacle;

Fig. 4 is a sectional view on the line 4—4,

Fig. 3;

20 Fig. 5 is a detached perspective view of the inner shell and the intermediate locking member; and

Fig. 6 is a perspective view showing the locking member on the inner shell.

Referring to the drawings, 1 is the insulated body of the receptacle having a deep flange 2, which is cutaway at 3 to receive the terminal 4 of the ordinary construction. The base of the insulated body is recessed at the opposite side for the reception of the 25 other terminal 5, which extends through a slot 6 in the body and into a recess 7 at the back of the body. The terminal, in the present instance, is threaded for the reception of the contact screw 8.

30 35 When the parts are assembled, the recess at the back is closed by any suitable non-conducting material 9. Within the flange 2 of the body portion is a threaded metallic shell 10, which is formed as shown in Fig.

40 45 50 55 5 When the parts are assembled, the recess at the back is closed by any suitable non-conducting material 9. Within the flange 2 of the body portion is a threaded metallic shell 10, which is formed as shown in Fig.

40 45 50 55 5 When the parts are assembled, the recess at the back is closed by any suitable non-conducting material 9. Within the flange 2 of the body portion is a threaded metallic shell 10, which is formed as shown in Fig.

40 45 50 55 5 When the parts are assembled, the recess at the back is closed by any suitable non-conducting material 9. Within the flange 2 of the body portion is a threaded metallic shell 10, which is formed as shown in Fig.

40 45 50 55 5 When the parts are assembled, the recess at the back is closed by any suitable non-conducting material 9. Within the flange 2 of the body portion is a threaded metallic shell 10, which is formed as shown in Fig.

Referring to Fig. 3, 13 designates a shell of less diameter than the shell 10, and having a screw thread formed thereon. Between the two shells is a locking member 14, which consists of a coiled spring wire having a hook 15 at one end that extends into a hole 16 in the inner shell 13. The opposite end of the wire is free. When it is desired to reduce the diameter of a receptacle, the coiled wire locking member 14 is screwed onto the shell 13, as shown in Fig. 6. The hook 15 of the locking member 14 enters the hole 16 so as to lock the inner end of the spring locking member to the shell. Then the shell 13, with the locking member thereon, is screwed into the shell 10. The coil yields under pressure so that it will enter the outer shell 10. When the inner shell is screwed in to its full extent, it cannot be turned in the reverse direction, as, the moment pressure is applied, the spring locking member expands and holds the inner shell firmly in a fixed position. The locking member may be modified without departing from the essential features of the invention, which is to lock the shell of less diameter to the outer shell so that it cannot be removed maliciously.

The invention hereinbefore described is especially designed for reducing the openings in the receptacles that have been installed. The inner shell and the spiral retaining devices are made as articles of manufacture and are sold independently of the receptacles in order that an electrician can screw the shell, and its retaining device, in the standard shell of a receptacle so that, when the shell of reduced diameter is in place, it cannot be removed.

This construction obviates the necessity of removing one receptacle having a shell of a given size and replacing it with another receptacle having a shell of less diameter to accommodate fuse plugs having less amperage than the standard plugs.

I claim:

1. The combination in a reducing device 100 for receptacles, of a receptacle having a threaded shell, and a second shell within the shell of the receptacle, said inner shell having a screw-thread adapted to receive a helical spring on the outside and to receive 105 a plug on the inside; and a helical spring

located in the groove of the thread on the outside of said inner shell and attached to said inner shell.

2. The combination in a reducing device for electric receptacles, of a receptacle having a threaded shell therein; a second shell having its wall shaped to form an inner and an outer screw-thread; and a helical spring

mounted on the outside of said inner shell and fitting the thread thereon and the thread of the receptacle shell, said spring being attached at one end to the inner shell, the internal thread of said inner shell being arranged to receive a plug.

MONRÖE GUETT.
